UNITED STATES PATENT OFFICE.

ARTHUR W. PITHOUSE, OF PHILADELPHIA, PENNSYLVANIA.

NECKWEAR-ATTACHING DEVICE.

Application filed December 4, 1922. Serial No. 678,439.

To all whom it may concern:

Be it known that I, ARTHUR W. PITHOUSE, a citizen of the United States, residing in the city and county of Philadelphia, State 5 of Pennsylvania, have invented a new and useful Neckwear-Attaching Device, of which the following is a specification.

My invention consists of a device attachable to an article of neckwear such as a bow tie 10 so as to support the same and attachable to a collar whereby said article may be conveniently adjusted to a collar and retained firmly thereon.

The invention is satisfactorily illustrated 15 in the accompanying drawing, but the important instrumentalities thereof may be varied, and so it is to be understood that the invention is not limited to the specific details shown and described, as long as they 20 are within the scope of the claims.

Figure 1 represents a front elevation of a neckwear attachment embodying my invention.

Figure 2 represents a rear elevation 25 thereof.

Figure 3 represents a top edge view thereof in normal condition.

Figure 4 represents a top edge view thereof in operative condition on a collar.

Figure 5 represents a transverse section 30 on line 5—5 Figure 4.

Figure 6 represents a rear elevation showing the device in connected position on a tie, and the latter in adjusted position on a 35 collar. Figure 7 represents a section on line 7—7 Figure 3, on an enlarged scale.

Similar numerals of reference indicate corresponding parts in the figures.

Referring to the drawings. 40 1 designates clips on opposite sides of a clevis or loop 2 which latter comprises the centre of the device and serves as a hinge allowing flexibility of the device, whereby the clips may be readily manipulated to be presented to and fitted on a collar.

Each clip comprises a pair of resilient limbs 3 and 4 composed of a piece of sheet metal wire or other suitable material bent on itself whereby said limbs are opposed to each other and are connected at the bend 50 which forms the eye 5 which is mounted on the sides of the clevis or loop 2 and forms an axis for the limbs so that the latter can readily turn on said clevis and so provide 55 the flexibility of the device.

On the axial ends of the limbs 3 are the

brackets 6 which are turned angularly thereof and pass freely over the corresponding ends, their outer terminals having mounted thereon by the pivots 7, the levers 8 which are angular in form, one limb 9 of each of which comprises a short tongue which is adapted to bear against the limbs 4 adjacent to said pivots 7 and thus force said limbs towards the limbs 3 of the clips and thus 60 pinch the clips tightly on a collar, as will be hereinafter more fully described and as best shown in Figure 4.

The other limbs 10 of said levers 8 extend 70 from the pivots 7 in the longitudinal direction of the clips, their free ends being adapted to pierce the fabric of the tie through slits 11 therein see Figure 6, the device being furthermore connected with and retained on the bow by what is known as the 75 central cross piece of the latter as shown dotted in Figure 6.

It will be seen that the clips may be separated to a sufficient extent by pressure on the levers 8. The fabric of the tie yielding 80 to allow movement of the levers. Then the clips are presented to the front edges of the body of a collar and pushed thereover so as to be in adjusted position on the collar. Then the levers are pressed inwardly towards the 85 limbs 4 of the clips when the tongues 9 of the levers ride over said limbs 4 in a direction towards the axial eyes of the clips when the limbs 4 are closed against the collar, and the latter is pinched between the limbs 3 and 90 4. As the tongues 9 have passed their centres, the limbs of the clips are prevented from separating and so the clips remain connected with the collar, and the tie is held 95 nicely in adjusted position on the collar and retained firmly thereon.

As the opposite clips are flexibly connected by the clevis 2 the former may be consequently manipulated each pair of clips being movable by itself in order to present 100 the pairs of clips successively to the opposite edges of the body of a collar and then push the clips home into proper engagement with the collar and adjust the tie properly thereon, as hereinbefore explained.

Having thus described my invention what I claim as new and desire to secure by Letters Patent, is:—

1. A device for attaching an article of neckwear to a collar consisting of a clip 110 formed of parallel pairs of limbs between which the edge portions of a collar may be

received, a central loop to which said pairs of limbs are connected and a lever mounted upon each of the inner of said limbs adapted to engage the limbs and thereby close 5 the limbs on the collar and retain the clip tightly thereon.

2. In a device for attaching an article of neckwear to a collar, a clip formed of limbs between which the edge portion of a collar 10 may be received, a lever adapted to close said limbs tightly on the collar, said lever being adapted to be moved about its axis so as to enter the article and provide the means of connection of said article with said device.

3. A device for attaching an article of

neckwear to a collar consisting of opposite clips composed of parallel limbs between which the edge portion of a collar may be received, a central loop to which said opposed clips have foldable relation, and pivotal levers on the clips adapted to close the latter and pinch them tightly on the collar, said levers being adapted to be moved about their pivot points so as to enter an article of 20 neckwear and provide means of connecting same to said device. 25

ARTHUR W. PITHOUSE.
